UNITED STATES PATENT OFFICE.

ELIAS STEIN, OF BOSTON, MASSACHUSETTS.

ROTARY CUTTER HEAD.

Application filed January 26, 1928. Serial No. 249,742.

This invention pertains to shoe manufacture and more particularly to a rotary cutter head for sole and heel edge trimming machines. In accordance with usual practice 5 the cutter head is of fixed width in an axial direction, and as its blades usually comprise portions for trimming the upper and lower corners of the sole, as well as the outer edge proper, it is necessary to have a separate cutter head for each different thickness of sole. In accordance with the present invention I have provided a cutter head of simple and durable construction which automatically accommodates itself to soles of a wide range of 10 thickness, thus avoiding the expense of keeping on hand a large assortment of cutters, as well as the waste of time incident to changing cutters of fixed width or manually adjusting cutters of variable widths. To this end, 15 I provide a main cutter having blades which are adapted to engage only the outer edge of the sole or, in accordance with a modified arrangement, the outer edge and the upper or rand surface of the sole, together with an auxiliary cutter adapted to slide axially with 20 reference to the main cutter and having blades shaped to give the desired contour or bevel to the lower corner of the sole. This auxiliary cutter is normally held by a spring in a position such that it is operative to trim the 25 thinnest sole for which the cutter head is designed, but this cutter yields in opposition to the pressure of its spring when a thicker sole is presented to the cutter head, and thus automatically accommodates itself to such 30 thicker sole. When the main cutter, in accordance with my preferred arrangement, is not provided with blade portions for trimming the rand surface of the sole (which I 35 believe in most instances is wholly unnecessary), I prefer to provide a guard plate which is movable axially with reference to the main cutter and urge it by means of a spring toward the auxiliary cutter, but, alternatively, 40 and particularly when the main cutter blades are provided with rand trimming portions, I employ a fixed guard or guide plate of usual type adapted to enter between the upper surface of the sole and the adjacent portion of 45 the upper of the shoe.

In the accompanying drawings,

Fig. 1 is a side elevation, partly in vertical section, illustrating the preferred form of my invention, in which both the auxiliary 50 cutter and the guard are movable axially with reference to the main cutter;

Fig. 2 is a vertical section illustrating a modified arrangement in which the auxiliary cutter is axially movable but in which the guard is fixed with reference to the main 60 cutter;

Fig. 3 is a diametrical section illustrating a cutter of usual form;

Fig. 4 is a composite fragmentary front elevation and section illustrating a preferred 65 form of main cutter such as employed in the arrangement shown in Fig. 1;

Fig. 5 is a similar section showing a cutter such as employed in the arrangement of Fig. 2, and

Fig. 6 is a side elevation of the auxiliary cutter.

The numeral 1 designates a portion of the frame of the edge trimming or heel trimming machine and which is provided with the rotating shaft 2 for carrying the cutter head. In Fig. 3 I have illustrated a usual type of cutter comprising the cylindrical body 3 having the blades 4 projecting therefrom, each blade comprising a portion which is substantially 75 straight for trimming the outer edge of the shoe sole, a portion 5 for trimming the rand or upper corner of the sole, and a portion 6 for trimming the lower corner of the sole. In such a cutter the parts 5 and 6 are fixed 80 relatively to each other and thus such a cutter is adapted for trimming soles of but one thickness.

In accordance with my present arrangement I employ a main cutter, such as shown 90 in Figs. 1 and 4, having the cylindrical body portion 7 and the blade 8 which are substantially uniform in width from end to end. The cutter 7 is mounted on the shaft 2 and held in position thereon in any desired manner. At a point between the cutter 7 and the frame 1 I mount a sleeve 9 on the shaft. This sleeve is provided with an annular chamber 10 concentric with shaft 2 and which receives a collar 11 secured to the shaft 2 by 95 means of a set screw 12 which projects outwardly into a longitudinally extending slot 13 in the sleeve 9. This set screw thus fixes the collar 11 to the shaft and also compels the sleeve 9 to turn with the shaft, although 100 permitting the sleeve to move axially to a limited extent as determined by the length of the slot 13.

A spring 14 bears at one end against the collar 11 and at its other against the inner 110 end of the auxiliary cutter 15 which has screw-threaded engagement with the sleeve 9. This

cutter 15 is provided with blades 16 which are disposed in the spaces between the blade 8 of the main cutter 7, and the blades 16 are provided with cutting edges 17 of the desired contour to give the beveled or other form to the lower corner of the shoe sole. If desired, the main cutter 7 may be loose on the shaft and receive its rotary motion through the engagement of the blades 16 and 8.

10 In the arrangement shown in Fig. 1 I extend the shaft 2 beyond the main cutter 7, and on this extended and preferably reduced portion of the shaft 2 I mount a second sleeve 18 having an annular chamber 19 which receives a collar 20 secured to the shaft by means of a set-screw 21 whose upper end enters an elongate slot 22 in the sleeve 18. A spring 23 encircling the shaft 2 bears at one end against the collar 20 and at its other against a guard member 24 having screw-threaded engagement with the sleeve 18. This guard is of annular form and has a series of circumferentially spaced slots separated by the inwardly directed ribs 25 which enter between the blades 8 of the main cutter 7. This guard is provided at its right-hand edge, as indicated in Fig. 1, with a radial flange 26 constituting the guard proper and which is adapted to enter between the upper or rand surface of the sole and the upper of the shoe.

30 As shown in Fig. 1, the parts are adjusted to receive a shoe sole of minimum thickness between the guard 26 and the cutting edge 17 of the blade 16 of the auxiliary cutter. If a shoe sole of greater width be applied to the rotating cutter, the auxiliary cutter 15 will be forced to the right by the pressure of the sole thereagainst and will thus automatically accommodate itself to a sole of any thickness within the range for which the cutter head is designed. By providing the axially movable guard 26, the necessary movement of the cutter 15 to accommodate a wider sole is reduced and the entrance of a very thick sole into engagement with the cutter is facilitated.

45 Referring to Figs. 2 and 5, I employ the same auxiliary cutter 15 as shown in Fig. 1, but in this arrangement I employ a main cutter 28 having the blades 29 which are provided with the rand trimming portions 30, and I employ a fixed guard 26^a secured to the end of the shaft by means of a screw 27. In this construction the entire adjustment for different thicknesses of sole is taken care of by the

movement of the auxiliary cutter 15, and the rand trimming portion 30 of the main cutter is maintained in definite relation to the upper surface of the sole by the action of the guard 26^a.

50 I claim:

1. A cutter head of the class described comprising a main cutter, a guard device having a portion adapted to enter between the upper surface of the shoe sole and the shoe upper, a sleeve movable axially with respect to the main cutter, the guard device being secured to one end of the sleeve, and a spring within the sleeve normally urging the guard device toward the main cutter.

2. A cutter head of the class described comprising a main cutter having blades for trimming the outer edge of a shoe sole, an auxiliary cutter having blades for trimming the lower corner of a shoe sole, said auxiliary cutter being movable axially with reference to the main cutter, and a guard device having a part adapted to enter between the upper surface of the shoe sole and the shoe upper, said guard device also being movable axially with reference to the main cutter, and spring means normally holding the guard device and the auxiliary cutter at a minimum distance apart but permitting said guard device and auxiliary cutter to separate under the pressure of a shoe sole whereby to accommodate shoe soles of different thicknesses.

3. Apparatus of the class described comprising a rotating shaft, a main cutter mounted upon the shaft, said cutter having spaced blades, a sleeve mounted upon the shaft, said sleeve having an annular chamber between it and the shaft, a collar within said chamber, a set screw securing the collar to the shaft, said set screw projecting into an axially elongate slot in the sleeve, a guard device secured to the end of the sleeve, a spring encircling the shaft and bearing at one end against the collar and at the other against the guard device, said guard device comprising a portion having ribs and intermediate slots, the slots being adapted to receive the blades of the main cutter, said guard device also comprising a radial flange adapted to enter between the upper surface of a shoe sole and the shoe upper.

55 Signed by me at Boston, Massachusetts, this 21st day of January, 1928.

ELIAS STEIN.
